UNITED STATES PATENT OFFICE.

GEORGE M. SCOTT AND HERBERT H. SCOTT, OF CHICAGO, ILLINOIS.

AUTOMOBILE-LOCK AND IGNITION-SYSTEM TESTER.

1,262,704.

Specification of Letters Patent. Patented Apr. 16, 1918.

Application filed April 8, 1916. Serial No. 89,947.

To all whom it may concern:

Be it known that we, GEORGE M. SCOTT and HERBERT H. SCOTT, subjects of the King of Great Britain, and residents of the city 5 of Chicago, county of Cook, and State of Illinois, have jointly invented a new and useful Automobile-Lock and Ignition-System Tester, of which the following is a specification.

10 Our invention relates to improvements in automobile accessories, the present invention being designed for use in connection with automobiles to serve as an effective lock against starting of the engine, and at the 15 same time as an efficient means for readily and easily locating the defective ignition circuit in the event of fouling of one or more of the cylinders of the engine.

The object of our invention is the production 20 of a device of this character which will be of durable and economical construction and highly efficient in use.

Other objects will appear hereinafter.

The invention consists in the combinations 25 and arrangements of parts hereinabove described and claimed.

The invention will be best understood by reference to the accompanying drawing forming a part of this specification, and in 30 which,

Figure 1 is a perspective view, in dotted lines, of the front end portion of an automobile equipped with a device embodying the invention,

35 Fig. 2 is a partially sectional top plan view of the device detached,

Fig. 3 is a section taken on line 3—3 of Fig. 2,

Fig. 4 is a front elevation of the device, 40 and

Fig. 5 is a plan view of the locking plate of the device detached.

The preferred form of construction, as 45 illustrated in the drawing, comprises a rectangular block or body 6 of insulating material which is mounted in a suitable metallic housing 7 which is adapted, when the device is in use, to be secured upon the dash board of the automobile in connection with 50 which the device is employed.

In one side of the block 6 is provided a plurality of spaced contact members 9 of conducting material which are threaded into said block. The outer ends of said 55 members 9 are perforated as at 10 for the

connection therewith of the conductor wires of the ignition circuits of the automobile in connection with which the device is used. Tubular guards 11 of insulating material inclose the outer ends of contact members 60 9 which serve an obvious purpose.

Slidably mounted in the opposite side of the block 6 in axial alinement with the contact members 9 are exteriorly projecting plungers 12 of insulating material, the inner 65 ends 13 of said plungers 12 being formed of conducting material and being recessed at their inner terminals for the reception of terminal members 14 which are yieldingly connected with the end portions 13 by means 70 of helical compression springs 15. In the depression of plungers 12, terminal members 14 are adapted to engage with the contacts 9, the yielding connection of the members 14 with the plunger portions 13 insuring 75 constant connection of the same with the contacts 9 in the depression of said plungers. The plunger portions 13 project through a perforated plate 16 of conducting material, said plate 16 being electrically 80 connected with the housing 7, which in turn is suitably grounded, as illustrated at 16'. With this arrangement, it will be seen, that the plunger portions 13 are constantly 85 grounded, and so that upon engagement thereof with the contacts 9, the latter will also be grounded.

The plungers are normally held at their outer terminals of movement by means of helical compression springs 17, said plungers being adapted to be locked in depressed positions or at their inner terminals of movement by means of a plate 18 which is shiftably mounted in housing 7. Said plate 18 is formed with key-hole slots 19 through 95 which the plungers project, the reduced portions of said slots, when said plungers are at their inner terminals of movement being adapted for engagement with circumferential grooves 20 provided in said plungers, as 100 clearly shown in the several views. The plate 18 is formed at one end with an exteriorly projecting handle 21 for effecting shifting of the same, the opposite end of said plate being formed with a flange 22 105 adapted for engagement by a bolt 23 of a lock 24 whereby said plate may be locked in operative or locking position, relative to the plungers 12. The lock 24 is of conventional type, being operable by means of a 110

key which will be carried by the driver of the automobile upon which the device is used.

In using the device, the same is interposed 5 in the ignition circuits of the engine of the automobile, the contact members 9 being connected with the conductor wires 25 of said ignition circuits which extend from the terminals of the magneto 26 of the vehicle 10 to the spark plugs 27 thereof. Each of said contact members 9 is of course connected with the conductor wires 25 of one pair of terminals, that is one terminal of the magneto and one terminal of one of the spark 15 plugs. With this arrangement, it will be seen that when the plungers of the device are in normal or outward position, the current from the magneto will flow on uninterruptedly to the spark plugs. By simply 20 depressing said plungers, however, it will be seen that any of the circuits from the magneto may be grounded, it being clear that in the event of depression of any of said plungers, when the current from the 25 magneto reaches the corresponding contact 9, instead of said current proceeding on to the spark plug, the same will follow the course of least resistance and in so doing will pass through the depressed plunger to 30 the plate 16 and thus be grounded. Thus, it will be seen, that any one of the spark 35 plugs may be cut out, making it possible, through a process of elimination, to locate the fouling spark plug, or spark plugs, in case of ignition trouble with the engine. It will be seen that such testing may be readily and expeditiously effected by the automobile driver from his seat in the vehicle by simply depressing the various plungers.

40 When it is desired to lock the engine against operation, it is only necessary to depress all of the plungers and then shift the plate 18 to operative position and lock

the latter by means of the lock 24. When this is done, it will be seen that all of the 45 ignition circuits of the engine cylinders will be grounded, rendering it impossible to at all start the engine.

While we have illustrated and described the preferred form of construction for carrying our invention into effect, this is capable of variation and modification without departing from the spirit of the invention. We, therefore, do not wish to be limited to the precise details of construction set 55 forth, but desire to avail ourselves of such variations and modifications as come within the scope of the appended claim.

Having described our invention what we claim as new and desire to secure by Letters 60 Patent is:

The combination with an internal combustion engine, with a cut-out device interposed in the ignition circuits of the engine between the terminals of the source of electrical energy and the spark plugs of the engine, said device comprising a block of insulating material provided with a plurality of transverse parallel passage ways, 65 plugs threaded in one end of said passage 70 ways and to which the wires of the circuit are attached, compressible plungers mounted in the opposite ends of said passage ways and adapted upon depression to engage said plugs, a ground plate in constant engagement with said plungers and means for locking said plungers in depressed position, 75 substantially as described.

In testimony whereof we have signed our names to this specification in the presence 80 of two subscribing witnesses.

GEORGE M. SCOTT.
HERBERT H. SCOTT.
